UNITED STATES PATENT OFFICE

MINOR F. H. GOUVERNEUR, OF BALTIMORE, MARYLAND, ASSIGNOR TO LOCKE INSULATOR CORPORATION, OF BALTIMORE, MARYLAND, A CORPORATION OF MARYLAND

INSULATOR

Application filed July 1, 1926. Serial No. 119,954.

The invention relates to insulators for high potential lines.

The primary object of the invention, generally stated, is to provide an insulator equipped with means whereby a large portion thereof will be kept dry at all times, thereby reducing danger of flash-over.

The object of the invention, more specifically stated, is to provide an insulator of the rod type including an elongated shank or body of insulating material and equipped with rain shields or guards acting to maintain the surface dry.

I am aware that it has been proposed to form an insulator with an integral outstanding skirt located immediately above the bottom cap but the shielding of the bottom cap is useless or at least substantially so. Furthermore there are many actual manufacturing difficulties involved in the making of an insulator of this character owing to the liability of warping and cracking during the steps of forming, drying and firing. It is for these reasons that I have made the present invention which has for an object the provision of an insulator equipped at an intermediate point and also at its upper end with shields or guards which will act to keep the surface dry, these shields being metallic and being secured to the porcelain or other insulating body.

An important object of the invention is to provide a guard or shield secured to the insulating body by a peculiar joint which will permit expansion and contraction under temperature variations without, under any circumstances, permitting water to seep along or otherwise gain access.

Another object of the invention is the provision of an insulator in which the insulating body is of a simple rod form easy and inexpensive to make as compared with those of more elaborate form but which will, nevertheless, have increased efficiency.

Many difficulties are encountered when an attempt is made to secure a skirt, guard or shield of metal to a body of insulating material but in carrying out the present invention I have devised a method of attachment which is practical and easily carried out.

To the attainment of the foregoing and other objects and advantages the invention preferably consists in the arrangement, combination and detailed construction to be hereinafter more fully described and claimed, and illustrated in the accompanying drawings in which:

Figure 1 is a view partly in elevation and partly in section of an insulator constructed in accordance with the invention.

Figure 2 is a greatly enlarged fragmentary detail section showing the joint between the guard or shield and the porcelain body, and

Figure 3 is a detail section through the depending flange of the guard or shield illustrating the method involved in making the joint.

Referring more particularly to the drawings, I have shown the insulator as including an elongated body member 1 of insulating material, such as porcelain, the ends 2 of the body being preferably slightly conical and sanded. At its intermediate portion the body is provided with a sanded belt or portion 3 which is preferably somewhat raised with respect to the remainder.

Engaged and suitably secured on the ends 2, as by means of cement 4 are caps of any ordinary or preferred type but here shown as formed respectively with sockets and heads. The purpose of these caps is to effect connection of any desired number of insulators in a string as is a common practice. Carried by the upper cap is a guard or shield 5 of any preferred variety but here represented as of sheet metal construction with a rolled edge 6 and a flange portion 7, the former being provided for stiffening purposes and the latter for engagement upon the upper cap.

A very important feature is the provision of a rain guard indicated generally by the numeral 8. This guard is formed preferably of cast iron and is of disk or ring-like form with a downward pitch so as to shed water. This guard is located at the intermediate portion of the insulator body and is secured thereto at the sanded belt 3. The guard is formed centrally with a depending flange 9 having an internal diameter slightly greater than the diameter of the insulator body at the

100

sanded belt. In the actual construction of the rain shield or guard it is preferable that the flange 9 be provided with holes 10 at points adjacent the merging of the flange into the undersurface of the guard. At these holes the flange is nicked, notched or otherwise formed to provide grooves 11 which extend from the holes to the lower edge. A suitable expanding tool is inserted within the flange, or any other suitable means may be employed, for the purpose of cracking the flange at these thinned portions. The guard or shield is then galvanized in a well known manner and the cracks will of course be covered by a skin. As a matter of fact the cracks are imperceptible and the formation of the skin over them is rather fortuitous and a mere consequence of the galvanizing, rather than the result of deliberate design.

Assuming that the shield or guard has been constructed as indicated or in some other equivalent manner, it is placed upon the insulator body at the sanded belt 3, the lower portion of the belt being coated with powdered copper or the like so that the flange 9 may be soldered directly onto the insulator body. The exact manner of applying the solder may be an immaterial detail but I have discovered that the application of a powdered metal to the sanded belt will permit the soldering of the shield in place. The solder is indicated at 12 in Figure 3. The space between the insulator body and the opening in the shield or guard may then be filled with an asphalt compound such, for instance, as what is known commercially as "Sarco", as indicated at 13, the purpose being to exclude water so that freezing will not occur.

In view of the fact that the flange of the shield or guard is provided with a plurality of cracks it is clear that expansion may occur when the insulator structure becomes heated under the sun's rays. The slight skin which covers these cracks is more or less resilient and may stretch when expansion occurs. These features combined with the fact that the flange is actually soldered onto the insulator body will insure a close fit at all times, the flange hugging the insulator closely regardless of any and all temperature changes. It might be mentioned, in passing, that the holes 10 above referred to are provided simply for the purpose of limiting the cracks so there will be no danger of splitting the shield or guard itself.

Assuming that the insulator has been constructed and assembled as above described it will be seen that it will be very efficient inasmuch as the shield or guard 5 will protect the upper half and the shield or guard 8 the lower half so that the insulator body will be kept dry, at least throughout the major portion of its area, the danger of flash-over being consequently greatly reduced. As the guards or shields are metallic and simply

secured with respect to the simple rod-like porcelain body it will be seen that the cost of manufacture will be greatly reduced as compared with insulators having a skirt formed integrally with the body. Insulators with skirts are difficult and expensive to make owing to the liability of warping and cracking during the various steps involved in the making thereof. By providing the metal rain shields or guards and securing them in the above indicated manner to the rod-like body, the ceramic difficulties are eliminated and the cost of production reduced while at the same time the efficiency in every respect is greatly increased.

While I have shown and described the preferred embodiment of the invention, it should be understood that the disclosure is merely illustrative inasmuch as I reserve the right to make all such changes and variations as will widen the field of utility and increase the adaptability of the device, provided such modifications constitute no departure from the spirit of the invention or the scope of the claims hereunto appended.

Having thus described the invention, I claim:

1. In an insulator, an elongated body of insulating material provided with terminal caps, a metal rain shield engaged upon said body near the central portion thereof, said rain shield having a depending flange portion of an expansible and contractile nature embracingly engaging the insulator body.

2. In an insulator, an elongated body of insulating material provided with terminal caps, a metal rain shield engaged upon said body near the central portion thereof, said rain shield having a depending flange portion split throughout a portion of its length so as to be of an expansible and contractile nature, said flange embracingly engaging the insulator body, the insulator body having a sanded belt within the confines of said flange, and the split portion of said flange being soldered to the body at said belt.

3. In an insulator, an elongated body of insulating material having connecting means at the ends thereof, a metal rain shield disposed on the body at the intermediate portion thereof and formed with a depending flange portion secured to the body, said flange portion having longitudinal cracks therein extending part way of its length and being formed with holes at the inner ends of the cracks for preventing lengthening thereof.

4. In an insulator, an elongated body of insulating material having connecting means at the ends thereof, a metal rain shield disposed on the body at the intermediate portion thereof and formed with a depending flange portion engaging the body, the body having a sanded belt within the confines of said flange, said belt having a powdered metal coating, and said flange being soldered to

the belt at the coated portion, said flange portion being provided with cracks extending part way of its length permitting expansion and contraction in accordance with temperature changes, and means for excluding moisture from the cracks.

5. In an insulator, an elongated body of insulating material carrying caps and having a roughened belt intermediate its ends, a metal rain shield having a depending central flange portion embracingly engaging the body at said belt, said flange portion being cracked longitudinally at spaced points to permit expansion and contraction, the lower portion of said flange being soldered to the roughened belt, and a filling of asphalt-like material above the line of soldering and filling the space between the flange and the body for excluding moisture.

10 20 In testimony whereof I affix my signature.
MINOR F. H. GOUVERNEUR.
